UNITED STATES PATENT OFFICE.

JOSEPH PEYSER, OF MOUNT VERNON, NEW YORK.

SEAMING MECHANISM.

Application filed October 29, 1921, Serial No. 511,342. Renewed March 25, 1924.

To all whom it may concern:

Be it known that I, JOSEPH PEYSER, a citizen of the United States, and a resident of Mount Vernon, in the county of Westchester and State of New York, have invented certain new and useful Improvements in Seaming Mechanism, of which the following is a specification.

This invention relates to seaming mechanism for seaming the covers on containers of sheet material and has for its main object and feature the production of simple, effective and high speed means for double-seaming square or irregular-shaped cans.

15 In the accompanying drawings the invention is disclosed in a concrete and preferred form in which—

Fig. 1 is a vertical sectional view on the plane of line 1—1 of Fig. 2 through a seamer head embodying my invention.

20 Fig. 2 is a horizontal sectional view on the plane of line 2—2 of Fig. 1.

Fig. 3 is a vertical sectional view on the plane of line 3—3 of Fig. 1.

25 Fig. 4 is a horizontal sectional view on the plane of line 4—4 of Fig. 1.

In devices for seaming square or irregular shaped containers it will be understood that the seaming tools, in addition to the 30 normal in-and-out movement to perform the seaming operation, must also receive a movement following the varying shape of the container. If the container has sharp angular surfaces, as is frequently the case, difficulty is encountered in obtaining a high speed because of the short angular turns that must be made by the cam roller engaging the follow-cam. In order to obtain a less pronounced angularity of the follow-cam and thereby making it possible to move the parts at a higher speed, I employ a follow-cam the shape of which is complementary to that of the shape of the irregular-shape container. This follow-cam preferably controls several seaming tools and is mounted so as to have its center of rotation coincident with the center of the chuck and concentric with the seaming-cam thereby producing a compact structure capable 40 of high speed and adequate lubrication.

Seaming machines are divided into two classes, viz, those in which the container to be seamed rotates and the seaming tools are relatively stationary, and those in which the 45 container is at rest during the seaming operation and the seaming tools travel in an

orbit around the container. This invention is applicable to both of these forms. If the container rotates, then obviously the follow-cam must rotate at the same speed, 60 but when, as in the present instance the container stands still the follow-cam likewise stands still.

Referring to the particular form in which the invention is here embodied 1 indicates a chuck, here shown stationary, which is the complementary member of the usual pedestal (not shown). 2 is the seamer head carrying the tools 3. 4 is the follow-cam conveniently mounted on the chuck 70 and 5 is the seamer cam. 18 indicates the shape of the container to be seamed. In the present instance where the chuck is stationary the seaming head is given a number of revolutions, say sixteen, for each 75 seaming operation by means well known in the art and not shown and the seaming cam is given a different number of revolutions, say fifteen, so as to produce a net difference of one revolution between the seaming tools 80 and the seamer cam in a manner well understood to obtain the same result as would be obtained if the container were rotating and the seaming tools were relatively stationary. 85

The seaming tools are in the present instance carried by slides 6 which have a reciprocating movement in the seamer head. Any suitable means may be employed to impart the combined motion produced by the follow-cam and the seamer cam to said 90 slides and therefore to the tools, although the particular means here disclosed constitute in themselves valuable features of the invention. As here shown a follow-cam lever 7 is pivotally supported at 8 on the 95 seamer head and has a cam roll 9 engaging follow-cam 4; and pivotally mounted on the follow-cam lever is a seamer cam lever 10 in the shape of a bell crank having a cam roll 11 engaging seamer cam 5. As will be 100 noted the center of cam roll 11 is substantially coincident or in line with the center of pivot 8 so that the rocking movement of cam lever 7 will not vary the position of cam roller 11 in cam 5. Pivotally supported at 105 its central point, on that end of follow-cam lever which is opposite to the point where cam roll 9 is located, is a rocking lever 12, one end of which is pivotally connected to seamer cam lever 10 by means of link 13; and the other end of which is pivotally connected to slide 6 by means of link 14. It has 110

been noted above that cam roll 11 is substantially coincident with pivot 8. In detail the arrangement is as follows: One of the seaming tools 3 is a first-operation roller 5 and the other the second operation roller. When cam 5 moves cam roller 11 of the second operation roller to cause the latter to finish the seam, the centers of 11 and 8 are practically in line with each other because it is necessary during the finishing operation to follow the exact contour of the container, but since cam roller 11 of the first operation seaming tool travels in the same cam groove 5 as roller 11 of the second operation seaming tool, it will be understood that it must be slightly off-center with respect to 8 when the first operation seaming roller is in its innermost position because the first operation seaming roller must not move as far inwardly as the second operation seaming roller. From this it will be understood that slide 6 is controlled by the combined motion of the two cams, the follow-cam causing its cam lever to move in accordance with the shape of the container and the seamer cam causing the requisite in and out movement of the seaming tools during the seaming operation. As shown, there is a system of levers for each seaming tool, and both lever systems are actuated by the same cams.

In order to enable the operator to adjust the seaming tools to different sizes of containers the following expedient is provided: Slide 6 is provided with a slidable carrier 15 which mounts the seaming roller. Sliding movement of this carrier with relation to 6 is effected by threaded member 16 in threaded engagement with said carrier and rotatably and idly engaging slide 6. Bolt 40 and nut 17 are used to clamp the parts together when proper adjustment has been made.

I claim:

1. Seaming mechanism for square or irregular-shaped containers comprising: a chuck, a seaming head, a plurality of seaming tools carried by the seaming head, a follow-cam the shape of which is complementary to that of the container, a seamer cam, and connections for imparting the combined movement of the two cams to the seaming tools.

2. Seaming mechanism for square or irregular-shaped containers comprising: a chuck, a seaming head, a plurality of seaming tools carried by the seaming head, a follow-cam the shape of which is complementary to that of the container and the axis of which is coincident with the chuck, a seamer cam, and connections for imparting the combined movement of the two cams to the seaming tools.

3. Seaming mechanism for square or irregular-shaped containers comprising: a chuck, a plurality of seaming tools, a follow-

cam the shape of which is complementary to that of the container and the axis of which is coincident with the chuck, a seamer cam mounted concentric with the follow-cam, and connections for imparting the combined movement of the two cams to the seaming tools. 70

4. Seaming mechanism for square or irregular-shaped containers comprising: a chuck, a plurality of seaming tools slidably mounted, a follow-cam the shape of which is complementary to that of the container, a seamer cam, and connections for imparting the combined movement of the two cams to the seaming tools. 80

5. Seaming mechanism for square or irregular-shaped containers comprising: a stationary chuck, a follow-cam the shape of which is complementary to that of the container mounted on said chuck, a rotating seamer head, a seamer cam concentric with the follow-cam and rotating at a speed different from that of the seamer head, seaming tools carried by the seamer head, and connections carried by the seamer head for imparting the combined movement of the two cams to the seaming tools. 85 90

6. Seaming mechanism for square or irregular-shaped containers comprising: a chuck, a follow-cam the shape of which is complementary to that of the container, a seamer cam, a seaming tool, a follow-cam lever pivotally supported, a seamer cam lever pivotally supported on the follow-cam lever, and connections between the seamer 100 cam lever and the seaming tool. 95

7. Seaming mechanism for square or irregular-shaped containers comprising: a chuck, a follow-cam the shape of which is complementary to that of the container, a seamer cam, a seaming tool, a follow-cam lever pivotally supported, a seamer cam lever pivotally supported on the follow-cam lever, a cam roll carried by the seamer cam lever at a point substantially coincident with the pivotal support of the follow-cam lever, and connections between the seamer cam lever and the seaming tool. 110 105

8. Seaming mechanism for square or irregular-shaped containers comprising: a chuck, a follow-cam the shape of which is complementary to that of the container, a seamer cam, a seaming tool, a follow-cam lever pivotally supported, a seamer cam lever pivotally supported on the follow-cam lever, a rocking lever pivotally supported on the follow-cam lever, a link between the seamer-cam lever and the rocking lever, and a link between the rocking lever and the seaming tool. 115 120 125

9. Seaming mechanism for square or irregular-shaped containers comprising: a chuck, a seamer head, a follow-cam the shape of which is complementary to that of the container, a seamer cam, a seaming tool 130

- carried by the seamer head, a follow-cam lever also carried by the seamer head and pivotally supported thereon, a seamer cam lever pivotally supported on the follow-cam lever, a rocking lever pivotally supported on the follow-cam lever, a link between the seamer cam lever and the rocking lever, and a link between the rocking lever and the seaming tool.
- 10 10. Seaming mechanism for square or irregular-shaped containers comprising: a chuck, a seamer head, a follow-cam the shape of which is complementary to that of the container mounted on a center coincident with that of the chuck, a seamer cam concentric with the follow-cam, a seaming tool on the seamer head, a follow-cam lever pivotally supported on the seamer head, a seamer cam lever pivotally supported on the follow-cam lever, a rocking lever pivotally supported on the follow-cam lever, a link between the seamer cam lever and the rocking lever, and a link between the rocking lever and the seaming tool.
- 15 15. Seaming mechanism for square or irregular-shaped containers comprising: a chuck, a seamer head, a follow-cam the shape of which is complementary to that of the container mounted on a center coincident with that of the chuck, a seamer cam concentric with the follow-cam, a seaming tool on the seamer head, a follow-cam lever pivotally supported on the seamer head, a seamer cam lever pivotally supported on the follow-cam lever, a rocking lever pivotally supported on the follow-cam lever, a link between the seamer cam lever and the rocking lever, and a link between the rocking lever and the seaming tool.
- 20 20. Seaming mechanism for square or irregular-shaped containers comprising: a chuck, a seamer head, a follow-cam the shape of which is complementary to that of the container mounted on a center coincident with that of the chuck, a seamer cam concentric with the follow-cam, a seaming tool on the seamer head, a follow-cam lever pivotally supported on the seamer head, a seamer cam lever pivotally supported on the follow-cam lever, a rocking lever pivotally supported on the follow-cam lever, a link between the seamer cam lever and the rocking lever, and a link between the rocking lever and the seaming tool.

ing lever, and a link between the rocking lever and the seaming tool.

11. Seaming mechanism for square or irregular-shaped containers comprising: a stationary chuck, a rotating seamer head, a follow-cam the shape of which is complementary to that of the container carried by the chuck, a seamer cam concentric with the follow-cam and rotating at a speed different from that of the seamer head, a seaming tool carried by the seamer head, a follow-cam lever pivotally supported on the seamer head, a seamer cam lever pivotally supported on the follow-cam lever, a rocking lever pivotally supported on the follow-cam lever, a link between the seamer cam lever and the rocking lever, and a link between the rocking lever and the seaming tool.

Signed at New York city, in the county of New York and State of New York, this 27th day of October, 1921.

JOSEPH PEYSER.
